(57) **CLAIM**

The ornamental design for a fluted cutting tool, as shown and described.

DESCRIPTION

FIG. 1 is a front view of the fluted cutting tool, in accordance with the subject invention;

FIG. 2 is a side view of the fluted cutting tool, in accordance with the subject invention;

FIG. 3 is a top view of the tool in FIG. 2;

FIG. 4 is a bottom view of the tool in FIG. 2;

FIG. 5 is a section view taken along arrows "5—5" in FIG. 2; and,

FIG. 6 is a section view taken along arrows "6—6" in FIG. 2.

Broken line illustrations in the drawings are not part of the design sought to be patented.
